Bee Hive.

№ 8,875 X

Patented Jan 12, 1835.

June 12, 1853

To all to whom these Letters Patent shall come,
 know you that I William Groves a citizen of the United States have
 invented a "Fortified Bee Palace" on a new and original plan for which I have
 obtained a Patent under the Seal of the United States. The said invention has
 been pronounced by the best judges to be far superior to anything of the kind
 heretofore discovered for beauty, convenience and usefulness. The preservation of
 the bees, the procurement of pure and much larger quantities of honey without
 destroying or惊ing the bees - the great and remarkable increase of their number -
 the facility and ease with which the honey can be taken from the house without
 even disturbing their ingenious operations; these are some of the most obvious ad-
 vantages arising from the above mentioned invention. The following is a full and
 exact description of the construction and operation of said "Palace". The panels
 are made of different sizes, according to the number of bees, which they are to be
 commenced with, but the most ordinary size is one of the first length two to 6 inches
 wide, they are made of oak boards, pine or poplar. In gables are made
 wide, one precisely like the other. The gables are prepared, both ought to be
 scathed, inside and outside, quickly as on the drift, before the boards are laid
 on: first the centre, 16 in. high from the top and sides, then the ends, the square
 is then brought up to the ends, the top part is equally divided into five sections
 by allowing two inches in the top platform, and 1 inch above and below for
 the reception of large window glasses, of 4 inches high by 12 wide, so that five
 sections will be each 14 inches wide on the outside. The sections are then set in
 at 2 inches from the top platform and 13 inches wide, by 2 high. A glass 6 by
 8, is inserted on the inside of each end door from a little, low as a bed on it, on
 the outside, (and a hole 4 inches wide, square and 3 inches from the side is cut
 out with a rabit, to receive a slide level of $\frac{1}{2}$ of an inch thick. The lines struck
 with dots, (see draft,) ought to be marked on the inside of the gable ends, after
 the gable ends are thus alike prepared, ploughed, grooved and glued together,
 (and the boards all once planed off, warm the with a penit should then be
 applied to the edges of the gable ends and in all the joints of the boards, as they are

with 10 lbs stone, then small strips of hair in the width of 10 ft of the spaces
 under each side of boards of six inches wide through which the tin plate is
 inserted, in order to cut off the combs with glass bowls, are placed on the
 inner edges of the two side platforms, to receive the 10 lbs of the stones, and it
 so to keep the glass bowls, when the honey is to be, which is as representing
 long prongs to bowls, from slipping off, on each side there is a box over them of
 five squares, the three upper squares with the ends are secured fast, the two
 front squares are secured (are having as shutters with two square locks, by which
 the bowls are placed in a vent; in these boxes the operations of the workmen
 more easily, if you keep it by day, than in anything but open houses.
 When it is necessary on the top platform to receive the stones of 10 lbs each
 on the bottom having a hole in the center of each side, on the top there is a
 box and a stone, by which the honey is taken out on the summer season
 and a small glass of 3 m. has high 1/2 a long is put in the inside of each stone
 so, having holes so it to slip along on the outside through all the stones of
 it stays because the black and a box is to be applied to each stone, but then I was
 with the stones of pine boards are not used the first year, in the first year, after the
 house is put to its proper place, to the glass and honey putting on, first in
 the hives and boards as many as it may contain are placed on the top on the
 top platform. The hives are then shut up, on the outside around, boxes, with
 a stone made of a gift of tar, a box spoon full of sulphur a quart of clay, and
 some hot water; two small boards are secured on the two side platforms
 with tar under them at the top, as soon as the bees have run their combs
 down over all the boxes, and have sufficient maintenance to live
 through the winter, the boxes are then cut off with a wire or thread and
 a thin tin plate is slipped in under on the boxes in order to secure the honey
 after the old hives are taken of full of honey, and the boxes are saved in the
 "polished palace," then the boards on the side platforms are taken away, and
 the boxes with the above-mentioned boards are covered over, thus the bees have room to
 spread out in every direction, (are not idle.) When ever the 10 pounds
 boxes are entirely full, the tin plate is inserted the bottom boards
 taken out with new combs (are the poorest honey.) After the box is unsecured
 (are cut off with a wire, and the tin replaced, the boards are covered over)

idom, with a shelf 4 inches wide for the beds to light on, (leave an open space of an inch all along, like at a wind mill, in the eaves and ingrip of the one, in addition to enable them to roll out all offensive mallets and thus defend themselves, striking against all intruding insects.) A.B. The boards are all distended crossways on the inside before they are nailed on; afterwards runways from the mallets on the inside of the rails being 15 inches apart, crossways run lengthways 24, and 8 inches from the ends and sides, on the inside (and go with an allowance of the ends to be sawed off on the outside,) for small holes for the reception of upright sticks one inch square, thick. On the inside of these sticks, as before they are nailed on, holes are distended (run out, in the middle, on the top platform, 4 inches wide, are on the side platforms 3 inches wide round, one foot apart, or between every four rows of sticks.) The two side platforms are then nailed on; after they are level, a nail toward the top platform is driven down. The inside of the frame ought to be as light (and even as perfect) as, but the end doors should not be very light (and the outlet below right always to be left open in order to secure a proper ventilation, to prevent the body from smothering; a base can be made of live, 3 square feet of small timber, with beams, after the body is thus constructed, the ends are then rounded, and off round the body is smoothed all over, then the doors are cut out with a circular saw, commenced by boring a hole with a small auger tool, the same lumber being taken for the doors; small strips as latches, 11 inches wide and one eighth thick are glued and sprigged on around the edges of the doors, to cover the cracks. The holes are then bored in with a wood and iron auger, one and tenors 1/2 deep. Whenever the body is placed on its legs, which are 20 feet high by 4 inches thick, it is put off below, and strips of ten inches wide nailed on, crossways run lengthways, the legs are secured on from the outside right under the outmost uprights, in order that after they stand, they may be infilled. The side boards, 5 inches wide are then screwed on (the whole length square.) The sticks when pointed off at the ends, and on rounds, of 2 inches above in, are then put in. A.B. Two up sticks are on the inside, the ends are then hung, over the hanging two hang loose a rafter. The hinge on the two large side doors a shutter, are put in in two, eight inches from the i.

described, in abundance, in the same volume, in
 can be removed with the slightest danger or trouble. As soon as the bees
 run out their combs to the holes behind the doors, two other large bee-hives
 are screwed on, hole upon hole, or turn the doors with some of the above-men-
 tioned combs, thirty combs around the holes; when the slides are remov-
 ed, a great quantity of bees will come out of the hives into the cavity behind;
 and after they have worked their way into the empty ones they are removed
 others replaced for the reception of more, &c. from the main body below.
 The honey is taken in winter time, when a door is opened in a cold morning,
 upon the plate, is quite fast. The bees will retire and become stiffened
 from the combs around them in the meadow between the sticks,
 with a sharp pointed, thin bone, the plate, and a stick with its ad-
 side removed. Thus a stick full can be taken out from the woven basket
 built every morning, until the one half of it is conveyed away. In the spring
 these sticks are liable to be replaced; thus the honey of every other half can
 be taken out every winter. By pursuing this plan the bees continue in work-
 ing in winter, by picking up every other half and every summer, &c. &c. - but
 we know of these "honey-hives" so large as to contain upwards of three 'hds
 hundred, recommended with eight centuries. One hundred and sixty quarts
 of honey have been taken out of one house in one year. The superiority of
 this invention over anything of the kind hitherto in use, is unquestionable
 (an individual who has made use of this plan all concur in saying
 that the bees thrive better, and make ten times the quantity of honey which
 they did in the former places).

We now call upon by these presents, that we the undersigned
 have had a perfect trial and examination of all species "Patent Bee
 Hives," two summers (and we cordially believe that it will answer every
 purpose, as it is recommended; any person wishing to see a honey comb
 twice in two summers, eight feet long (are four wide) can be obtained with
 the right by calling with us. Jacob Parker, Cornelia St. in Harris, Penn.
 or 26th Philadelphia, Reading Berks County Pa. (December 9. 1834.
 On this 26th day of May, 1835, before the subscriber, a Justice of the Supreme

having personally appeared the aforesaid William Groves,
made solemn oath according to law, that he verily believes himself
to be the true and original inventor, or discoverer of the invention above
specified and described for a Bee Stinger, and that he is a citizen of the
United States.

G. H. Charlton.

Sworn under my hand, at the City of Washington this 12th day of June A.D.
1836. And I do know

By the President, John Forsyth, Secretary of State:
"I do certify that the foregoing Letters Patent, were delivered to me on the
13th day of June A.D. 1836, to be examined, and I have examined the same
and find them conformable to law."

B. H. Butler Attorney General of the
United States

James L. Conner
Letters Patent

Dec 14, 1836

The Schedule referred to in these Letters Patent, and making part of the
same, containing a description in the words of the said James L. Conner himself of his
Invention in Canal Boats for the Transportation of Merchandise.

Schedule or Specification of James L. Conner's Improved Canal Boat for carrying
machinery and general freight to be used when transhipment from Canal to Rail
or other roads and vice versa is necessary.

Construct the hull of the Canal Boats ~~where~~ in all respects similar to those
now in the Canal to be navigable. Construct a short stern deck such as is use say
four or five feet long next to which deck extend in 6 feet for a cabin. Also construct
a short fore deck say four or five feet long.

~~This deck must be well raised from fracture to sixteen feet in length~~
